WALTER H. WANGELIN, OF ST. LOUIS, MISSOURI

SAND-SLINGING APPARATUS

Application filed January 4, 1930. Serial No. 418,515.

This invention relates generally to molding apparatus and more specifically to an improved apparatus adapted for use in introducing sand into molding flasks, the predominant object of the invention being to provide an apparatus of this type which includes as a part thereof a swingable sand slinger which is so supported that same moves in a true horizontal plane during movement thereof.

10 Prior to this invention apparatus of the general type of that disclosed herein have been produced but in all of such apparatus with which I am familiar the swingable sand slingers were pivoted to a support in such 15 manner that said sand slingers moved in an arcuate path. This was a decided disadvantage inasmuch as it caused the streams of sand issuing from the sand slingers to be directed at an angle to the true perpendicular 20 when the sand slingers were moved from their normal perpendicular positions.

In the use of apparatus of the type disclosed herein a large flask or a number of smaller flasks are arranged on the molding floor at 25 the base of the apparatus and beneath the swingable frame which supports the sand slinger, and sand issuing from the sand slinger is directed into all parts of the large flask or successively into the various smaller 30 flasks. In the use of apparatus heretofore employed having the pivotally supported sand slingers referred to above, the sand would be directed into the smaller flasks located immediately beneath said sand slingers, or into the portion so positioned of a 35 larger flask, in the desired manner, that is to say the stream of sand would be directed perpendicularly into said flasks. However, when other flasks or other portions of a 40 larger flask were located in horizontal offset relation with respect to the sand slingers it was necessary that said sand slingers be swung on their pivots so that the stream of sand discharged therefrom may be directed into said 45 offset flasks or flask portions and where this was done the sand stream was directed at an angle with the consequent loss of precision in directing the sand into the flasks.

In the use of my improved apparatus the 50 sand slinger thereof is swingably supported

so that it always moves in a true horizontal plane, hence the sand stream discharged from said sand slinger will always be directed perpendicularly into any flask or flask portion located in the area covered by the swing 55 or throw of the sand slinger.

Another important feature of the present invention resides in the fact that the sand slinger is capable of universal horizontal movement, hence any flask located in the 60 area covered by the swing or throw of the sand slinger or any portion of a mold so located may receive sand from said sand slinger.

Figure 1 is a view of my improved apparatus showing same partly in vertical section 65 and partly in elevation.

Figure 2 is a plan view of the apparatus illustrated in Figure 1.

Figure 3 is a section of the sand slinger of my improved apparatus including a fragment 70 of the sand conductor leading thereto.

Figure 4 is a fragmentary detail illustrating a modification of preferred form of the invention.

In the drawing, wherein is shown for purposes of illustration, merely, several embodiments of the invention, A designates the improved apparatus which includes a base plate 1 adapted for attachment by suitable means to a suitable support 2. The base plate 1 is provided with an upstanding portion 3 which is provided in its top face with a ball raceway 4. 5 designates a base cap provided preferably with a downwardly extended circumferential flange 6 which embraces the upstanding portion 3 of the base plate 1, and 6' designates a ball raceway formed in the lower face of the top wall of said base cap. The raceways 4 and 6' are aligned vertically with respect to each other and 7 designates anti-friction balls which are arranged in said raceways and thus provide for free rotary movement of the base cap with respect to the base plate. The base cap 5 is provided with an outstanding lug 8 through which a bolt 9 is extended and the base plate 1 is provided with a plurality of screw-threaded apertures 10 into which the lower screwthreaded end portion of the bolt 9 may be screwed for the purpose of preventing undesired rotary 100

movement of the base cap 5 with respect to the base plate 1.

Fixed to the base cap 5 and extended upwardly therefrom is a pair of supporting elements 11 providing a standard, said supporting elements preferably, though not necessarily, being in the form of channel beams arranged back to back and in spaced relation as illustrated more clearly by dotted lines in Figure 2. Secured to the upper ends of the supporting elements 11 by suitable fastening devices 11' is a horizontally disposed supporting member 12 which may, if desired, be in the form of a channel beam arranged with its back wall at the bottom and its spaced side flanges extended upwardly. The spaced side flanges of the supporting member 12 provide a seat for a cylindrical housing 13, which at one of its ends is provided with an enlarged portion 14, and at its opposite end is provided with a downturned hollow portion 15. The interior of the enlarged portion 14 and the passageway through the hollow portion 15 communicate with the interior of the cylindrical housing 13, and arranged within said cylindrical housing is a screw conveyor 16, said screw conveyor being supported for rotation in suitable bearings 17, and rotary motion being imparted thereto by means of suitable motion producing means such, for instance, as an electric motor 18. The shaft of the screw conveyor and the drive shaft of the motor 18 are provided with suitably sized sprocket wheels over which a sprocket chain 19 operates whereby motion is transmitted from the motor to the screw conveyor.

Arranged in a vertical position adjacent to the supporting elements 11 is a conveyor housing 20, and arranged for operation within said conveyor housing is an endless conveyor 21. The endless conveyor 21 is of conventional design, comprising a sprocket chain 22 arranged for operation over sprocket wheels 23 arranged in the upper and lower portions of the conveyor housing. The sprocket chain 22 has buckets 24 fixed thereto in the manner common to conveyors of this type. At the lower end of the conveyor housing 20 same is provided with a hopper portion 25, and at its upper end said housing is provided with a horizontally disposed portion 20' which overhangs the enlarged portion 14 of the cylindrical housing 13. 26 designates a tapered conduit which provides means of communication between the interiors of the portion 20' of the conveyor housing 20 and the enlarged portion 14 of the cylindrical housing 13 respectively, and 27 designates an inclined deflector which terminates at its lower end at the conduit 26. The endless conveyor 21 is driven by suitable means such, for instance, as an electric motor 28 and motion is transmitted from said motor to the conveyor through suitable speed reduction gearing 29.

30 designates a suitable rectangular frame which supports at one of its ends the sand slinger 31 of my improved apparatus, said sand slinger being of the usual type employed for throwing sand in foundries, comprising a suitably shaped barrel 32 within which a revolving sweep 33 is arranged, said sweep being rotated at a high rate of speed by the electric motor 33'. The barrel of the sand slinger is provided with a discharge passageway 34 which is extended downwardly, and at its upper end said barrel is provided with an inlet conduit 35 which is shaped at its upper end to provide a socket 36. 37 designates a hollow sand conductor which leads from the cylindrical housing 13 to the barrel 32 of the sand slinger. The sand conductor 37 at its lower end is provided with a globular portion 38 which is seated in the socket 36 at the upper end of the conduit 35 leading to the barrel of the sand slinger 32. Likewise at the upper end of the sand conductor 37 same is provided with a socket 39 in which is seated a globular portion 40 formed at the lower end of the portion 15 of the cylindrical housing 13. It is obvious that the associated socket 36 and globular portion 38 provide a universally movable joint which is located at the lower end of the sand conductor 37, and that the socket 39 and globular portion 40 provide a second universally movable joint which is located at the upper end of said sand conductor 37.

41 designates a plurality of suspension elements which support the frame 30 and with it the sand slinger 31 which is supported by said frame. In the embodiment of the invention illustrated in Figures 1 and 2 there are four of these suspension elements, though more or less of said elements may be employed if desired, and each suspension element is connected at its upper end to the member 12 by means of a universally movable joint 42, and at its lower end each of said suspension elements is connected by means of a universally movable joint 43 to the frame 30. The universal joints 42 and 43 may be of any suitable type; that is to say they may be the conventional ball and socket joints illustrated, or they may be the type of knuckle joint commonly referred to as a universal joint.

Attached to the horizontal supporting member 12 by means of a universally movable joint 44 is a downwardly extended rod 45. The rod 45 is provided with a recess 46 formed longitudinally thereof and extended upwardly from the lower end of said rod. Connected to the frame 30 by means of a universally movable joint 46 is a rod 47, the last mentioned rod being of considerably less diameter than the rod 45 and being extended upwardly into the recess 46 of said rod 45. The lower portion of the rod 45 is screw-threaded as indicated at 48 and arranged on said screwthreaded portion of said rod is a

nut 49, and interposed between said nut and a shoulder 49' provided by a part of the universally movable joint 46 is a coil spring 50. The coil spring 50 is characterized by a tendency to elongate, hence it exerts a strong pressure in a downward direction.

In the use of my improved apparatus the discharge passageway of the sand slinger 31 will be arranged immediately above the flask or flasks (not shown) into which sand is to be introduced. Sand will then be shoveled into the hopper portion 25 of the conveyor housing 20 and the buckets 24 of the endless conveyor 21 (which travels in the direction indicated by the arrow in Figure 1) will carry said sand upwardly and will discharge said sand on the inclined deflector 27 whereby said sand will be directed through the conduit 26 and into the enlarged portion 14 of the cylindrical housing 13. The rotating screw conveyor 16 within the cylindrical housing will then convey the sand forwardly of said cylindrical housing and when it reaches the extreme forward end of the cylindrical housing 13 the sand will pass through the portion 15 and sand conductor 37 to the interior of the barrel of the sand slinger, and the rapidly rotating sweep 33 within said barrel will discharge said sand from the barrel of the sand slinger and direct same forcibly into the flasks.

As already stated herein the apparatus may be used in introducing sand into a number of flasks grouped at the base of the apparatus, or it may be used in connection with a single larger flask, and when this is so it is necessary to move the sand slinger so as to direct sand into all of the group of flasks or all parts of the larger flask. In the use of my apparatus the operator may grasp the frame 30 and move it in any direction desired due to the presence of the universally movable joints associated with the suspension elements 41, and because of the fact that each suspension device is provided with universally movable joints at opposite ends thereof the frame 30 and the sand slinger 31 will always move in a horizontal plane, hence the stream of sand issuing from said sand slinger will be directed perpendicularly into the flasks. The sand conductor 37 is connected in place in the apparatus by universally movable joints located at the opposite ends thereof, hence, said sand conductor will move with the frame 30 in a manner to maintain a conduit for sand passing to the sand slinger regardless of the position of said sand slinger.

The combined frame and sand slinger is quite heavy and it would, therefore, be a severe task for the operator to hold same in a shifted position to which it had been moved. I, therefore, employ the coil spring 50 which is so arranged that it exerts pressure in the direction indicated by the feathered arrow

in Figure 1. Due to the fact that the coil spring when the rod 45 has been moved out of a true perpendicular position, exerts downward and outward pressure against the frame 30 which pressure may be defined by a vertical and a horizontal component, said horizontal component of said pressure will assist in maintaining the frame in any position to which it has been adjusted, hence, the burden of the operator in holding the frame in positions to which it has been adjusted is lessened. The tension of the coil spring may be regulated by screwing the nut longitudinally of the screwthreaded portion 48 of the rod 45.

In Figure 4 I illustrate a modified form of the invention in accordance with which the rod 45, coil spring 50 and associated elements are eliminated, and instead thereof I provide each suspension element 41' with a counterweight 50' which is mounted thereon at the upper end thereof. The counterweights serve the same purpose as the coil spring 50; that is to say, when the frame 30' is moved to a position where the suspension elements 41' are located at an angle to the true perpendicular the counterweights will maintain said frame in such position.

Due to the swivel arrangement between the base cap 5 and the base plate 1 the frame 30 may be swung in a circle about the vertical axes of the supporting elements 11 whereby the sand slinger may be disposed above flasks grouped in a circle about the base of the apparatus. Also when the base cap has been located in a desired position same may be locked in such position with the aid of the bolt 9.

I claim:

1. An apparatus of the class described including a sand slinger, a support for said sand slinger, a suspension element, a substantially universally movable joint for connecting said suspension element to said support, and a second substantially universally movable joint which serves to connect said suspension element to said sand slinger.

2. An apparatus of the class described including a sand slinger, a support for said sand slinger, a frame by which said sand slinger is carried, a plurality of suspension elements for attaching said frame to said support, a substantially universally movable joint at one end of each suspension element for connecting same to said support, and a second substantially universally movable joint at the opposite end of each suspension element for connecting same to said frame.

3. An apparatus of the class described including a sand slinger, a support for said sand slinger, means for conveying sand toward said sand slinger, a frame by which said sand slinger is carried, a plurality of suspension elements for attaching said frame to said support, a movable joint at one end of each

5 suspension element for connecting same to said support, a second movable joint at the opposite end of each suspension element for connecting same to said frame, and a conduit for conducting sand from said sand conveyor to said sand slinger, said conduit comprising a hollow element, a movable joint for connecting said hollow element to said sand conveyor, and a movable joint for connecting said hollow element to said sand slinger.

10 4. An apparatus of the class described including a sand slinger, a support for said sand slinger, means for conveying sand toward said sand slinger, a frame by which said sand slinger is carried, a plurality of suspension elements for attaching said frame to said support, a movable joint at one end of each suspension element for connecting same to said support, a second movable joint at the opposite end of each suspension element for connecting same to said frame, and a conduit for conducting sand from said sand conveyor to said sand slinger, said conduit comprising a hollow rigid element, a movable joint for connecting said hollow element to said sand conveyor, and a movable joint for connecting said hollow element to said sand slinger.

15 5. An apparatus of the class described including a sand slinger, a support for said sand slinger, means for conveying sand toward said sand slinger, a frame by which said sand slinger is carried, a plurality of suspension elements for attaching said frame to said support, a movable joint at one end of each suspension element for connecting same to said support, a second movable joint at the opposite end of each suspension element for connecting same to said frame, and a conduit for conducting sand from said sand conveyor to said sand slinger, said conduit comprising a hollow rigid element, a movable joint for connecting said hollow element to said sand conveyor, and a movable joint for connecting said hollow element to said sand slinger, said movable joints associated with said suspension elements and said movable joints associated with said sand conductor being capable of substantial universal movement.

20 6. An apparatus of the class described including a sand slinger, a support for said sand slinger, a frame by which said sand slinger is carried, a plurality of suspension elements for attaching said frame to said support, a substantially universally movable joint at one end of each suspension element for connecting same to said support, a second substantially universally movable joint at the opposite end of each suspension element for connecting same to said frame, and means for maintaining said frame in positions to which it has been adjusted.

25 7. An apparatus of the class described including a sand slinger, a support for said

sand slinger, a frame by which said sand slinger is carried, a plurality of suspension elements for attaching said frame to said support, a movable joint at one end of each suspension element for connecting same to said support, a second movable joint at the opposite end of each suspension element for connecting same to said frame, and means including an expansible coil spring for maintaining said frame in positions to which it has been adjusted.

30 8. An apparatus of the class described including a sand slinger, a support for said sand slinger, a frame by which said sand slinger is carried, a plurality of suspension elements for attaching said frame to said support, a movable joint at one end of each suspension element for connecting same to said support, a second movable joint at the opposite end of each suspension element for connecting same to said frame, and means for helping to maintain said frame in positions to which it has been adjusted, said means including telescoping members, an expansible coil spring interposed between abutments associated with the respective telescoping members, a movable joint for connecting one of said telescoping members to said support, and a second movable joint for connecting another of said telescoping members to said frame.

35 9. An apparatus of the class described including a sand slinger, a support for said sand slinger, a frame by which said sand slinger is carried, a plurality of suspension elements for attaching said frame to said support, a movable joint at one end of each suspension element for connecting same to said support, a second movable joint at the opposite end of each suspension element for connecting same to said frame, and means for helping to maintain said frame in positions to which it has been adjusted, said means including telescoping members, an expansible coil spring interposed between abutments associated with the respective telescoping members, a movable joint for connecting one of said telescoping members to said support, and a second movable joint for connecting another of said telescoping members to said frame, said movable joints associated with said suspension elements and said movable joints associated with said telescoping members being capable of substantial universal movement.

40 In testimony whereof I have hereunto set my hand.

WALTER H. WANGELIN.
